UNITED STATES PATENT OFFICE.

CHARLES AUG. KÜNZEL, OF PHILADELPHIA, PENNSYLVANIA.

BALLOON.

SPECIFICATION forming part of Letters Patent No. 399,271, dated March 12, 1889.

Application filed June 28, 1888. Serial No. 278,414. (No model.)

To all whom it may concern:

Be it known that I, CHARLES AUG. KÜNZEL, a subject of the King of Saxony, residing in the city and county of Philadelphia, State of Pennsylvania, have invented a new and useful Improvement in Balloons, which improvement is fully set forth in the following specification and accompanying drawings.

My invention consists of improvements in balloons, as will be hereinafter fully set forth, and definitely pointed out in the claims.

Figure 1 represents a side elevation of a balloon constructed in accordance with and embodying my invention. Fig. 2 represents a top plan view of the ship or car and the propelling mechanism. Figs. 3 and 4 represent detail views of the rudder.

Similar numerals of reference indicate corresponding parts in the several figures.

Referring to the drawings, the numeral 1 designates the frame-work of my improved balloon.

The numeral 2 designates the balloon proper, which is constructed of silk or other suitable fabric, and is secured to the central portion of the frame-work.

The numeral 3 designates the charging-vessels which are secured to the frame-work on each side of the balloon, and are also connected with the balloon by means of the bars or plates 4.

The balloon 2 is provided with an outlet or discharge, 5, controlled by a valve, 6, and is connected with the charging-vessels by means of the pipes 7, for allowing the charging of the balloon from said vessels, and the pipes 7 are provided with valves 8. The charging-vessels are provided with inlet-pipes 9 for supplying the said vessels, and said pipes are provided with controlling-valves. The charging-vessels are also provided with openings or man-holes 10, covered by a door, 11, the purpose of which is to allow the entrance of air to said vessels, and outlets 12 are provided, the top of the charging-vessels having valves 12¹, the purpose of which is to allow the gas to pass out and also allow the air to pass out, which enter the vessels through the openings 10, which will allow the balloon to descend slowly and with perfect safety, as the air which enters the openings 10 will

serve to buoy up the balloon to a certain extent, or, in other words, sufficiently to permit it to descend slowly. This construction is applied merely as a safeguard, and is to be used when the balloon has been damaged and there is danger of an accident.

The numeral 13 designates the ship or car, which is connected with the frame-work by means of chains 14 or other desired means. Passing through the sides of the ship is a shaft, 15, having on each end a propelling-wheel, 16, and also having a driving-pulley, 17, around which passes the belt 18, driven by means of an electric motor, 19, of any preferred construction.

20 designates a vertical shaft carrying the propelling-wheel 21, said wheel being arranged to revolve above the ship, and on the shaft 20 is a driving-pulley, 22, over which passes the belt 23, driven by means of an electric motor, 24.

25 designates a vertical shaft carrying the propelling-wheel 26, arranged to revolve below the ship, and on the shaft 25 is a driving-pulley, 27, over which passes a belt, 28, driven by means of an electric motor, 29.

From this construction it will be observed that the propelling-wheels in the sides of the ship are driven by the same motor, and that independent motors are employed for driving the upper and lower propelling-wheels.

I would have it understood that I do not limit myself to the employment of electric motors as the driving or operating power for the propelling-wheels, as any mechanism which transmits power will answer the purpose. The blades of the upper and lower wheels are arranged in opposite directions, and the upper wheel is employed to cause the balloon to descend and the lower one to cause the balloon to ascend, and the side propelling-wheels are employed when it is desired to travel in a straight course.

30 designates a series of sails, wings, or blades, which are pivoted or hinged to the sides of the ship at the bow thereof or in front of the side propelling-wheels, and the said wings are adjustable to different angles by means of the rods 31, which pass through eyes 32 on the ship, and consequently the sails connected therewith are retained in the

desired angle by means of set-screws 33 in the eyes 32, as will be readily understood. The sails are of different sizes, the inner one being the smallest and the outer one the longest 5 of the set.

To the top of the ship in front of the upper propelling-wheel is pivoted a series of sails, 34, having adjusting devices 35, of similar construction to those on the side sails.

36 designates the rudder, pivoted to the stern of the ship, the said rudder being composed of a series of slats, 36, connected together by means of a rod, 37; and operated by means of cords 38. It will be observed that the rudder is constructed similar to a shutter and that the slats can be opened and closed and the rudder moved to the right or left, as desired, by means of the cords. When traveling in a straight line, the slats are open and 20 the rudder is in a right-lined position, as shown in Fig. 4 of the drawings. When it is desired to guide or steer to the right or left, the slats are closed and the rudder turned in the desired direction, as will be readily understood.

The operation of the balloon is as follows: When it is desired to rise, the lower propelling-wheel and the balloon effect this result, and when the proper height is obtained, and it is 30 desired to travel in a straight line the upper and side propelling-wheels and the sails are employed, the rapidity of travel being regulated or governed by the adjustment of the sails, and the rudder serving to guide or steer the balloon. When it is necessary to descend, the gas is allowed to pass out of the balloon and vessels slowly and the upper propelling-wheel only is allowed to revolve, causing the balloon to descend with ease and safety.

40 From the foregoing it will be observed that I provide a balloon which is entirely under control of the attendant or operator, which will travel on an upward or straight course and at any desired speed, which can be easily 45 guided, and which can be allowed to descend with ease and safety. The sails 30 on the ship can also be employed in steering the same by closing them on one side and opening them on the other.

50 Having thus described my invention, what I claim as new, and desire to secure by Letters Patent, is—

1. The combination of a ship, sails pivoted to the sides and top thereof at the bow, rods 55 connected to said sails, eyes through which

said rods pass, and set-screws in said eyes for engaging the rods, operating in the manner and for the purpose described.

2. In a balloon, the combination of the gas-envelope, a ship connected therewith, a propeller-wheel above the ship and another below the same, propeller-wheels on the sides of the ship, and adjustable wings at the bow of the ship, substantially in the manner and for the purpose described.

3. In a balloon, a frame, a gas-envelope suspended therefrom, charging-vessels on each side of the balloon suspended from the frame and connected with the balloon, a car or ship connected to the balloon and charging-vessels, a rudder carried by the car formed of a series of slats, a propeller-wheel above the ship and another below the same, propeller-wheels at the sides of the car, and adjustable wings in front of the side propeller-wheels and 75 above the car, said parts being combined, arranged, and operating substantially in the manner and for the purpose described.

4. In a balloon, the ship or car, the wings attached to the top of the ship, the said wings being of different lengths, and the wings attached to the bow of the ship, also of different lengths, substantially as and for the purpose described.

5. In a balloon, the combination, with the gas-envelope, the ship, and the propelling devices, of the adjustable wings secured to the top of the car of different lengths, and the adjustable wings secured to the front or bow of the ship, also of different lengths, arranged 90 and operating substantially in the manner and for the purpose described.

6. A balloon or aerial ship consisting of a balloon, charging-vessels, a ship connected with and depending from said balloon and 95 charging-vessels, propelling devices, substantially as described, carried by the ship, and mechanism, substantially as described, in said ship for operating the propelling devices, a rudder carried by the ship consisting of a series of slats, and adjustable wings arranged at the bow of the ship and of different lengths or sizes, said parts being combined, arranged, and operating in the manner and for the purpose described.
